RADIATOR ENCLOSURE

Tom V. Sawyer, Chicago, Ill., assignor of one-half
to Donald M. Crooks, Chicago, Ill.

Application April 22, 1946, Serial No. 663,853

1 Claim. (Cl. 237—79)

1

This invention relates to improvements in radiator enclosures and is more particularly concerned with an enclosure of a type having heat reflecting top, back, and end walls and a screened front wall through which air may circulate for passage around a radiator enclosed therein.

Radiator enclosures, usually provided primarily to conceal unsightly radiators, often lack means to insure the maximum heat radiation from the encased radiator, and further, are devoid of means to prevent objectionable overheating of the top of the enclosure. It is, therefore, an object of the invention to provide a radiator enclosure with means to prevent heating of the enclosure top so as to thereby enable use of such top as a stand for plants, flowers, or other articles of the kind that might be damaged when subjected to heat.

Another object of the invention is to provide a radiator enclosure structure of a kind that will prevent the movement of air into or out of the enclosure at the back and ends thereof and thereby avoid the setting up of current eddies around the back and ends.

Another object is to provide a radiator enclosure with walls completely encasing exposed portions of a radiator to prevent burning or other injury from contact therewith.

Another object of the invention is to provide a radiator enclosure that is not expensive to manufacture and which embodies novel means to insure maximum heat radiation without the overheating of any portion thereof.

Other and further objects of the present invention will be apparent from the following descriptions and claim and are illustrated in the accompanying drawing which, by way of illustration, shows a preferred embodiment and the principle thereof. Other embodiments of the invention embodying the same or equivalent principle may be used and structural changes may be made as desired by those skilled in the art without departing from the present invention and a purview of the appended claim.

In the drawing:

Fig. 1 is a perspective view of a radiator enclosure embodying features of the present invention.

Fig. 2 is a horizontal sectional view taken on line 2—2 of Fig. 1.

Fig. 3 is a vertical sectional view, partly broken away, taken on line 3—3 of Fig. 1.

Referring to the drawing, the radiator enclosure embodying the features of the present invention consists of a substantially rectangular

10 cabinet including a frame structure having vertically arranged corner posts 11 and horizontal stringers 12 extending between the corner posts. Wood panels forming a back wall 13 and end walls 14 are secured to the corner posts and stringers in any conventional manner as, for example, by means of wood screws 15 so as to completely enclose the back and ends of the enclosure. The front wall 15 is provided with a large 15 central opening over which a screen 16 or other open mesh material or grill work is arranged. The screen 16 may be secured to the margins of the front wall surrounding the opening as by means of molding strips 17 and an intermediate molding strip 18 may be provided to secure the medial portion of the screen 16 to a center post 19. Although the radiator enclosure illustrated 20 has but one center post 19 to reinforce the substantially open front of the enclosure, it should be understood that additional posts may be suitably arranged to bridge the front wall opening in such instances where the opening is of such size as to require additional reinforcement.

A top, generally indicated at 21, overlies the 25 upper open end of the wall structure described hereinabove and if desired, said top may be hingedly connected along its rear edge to the back wall 13 so as to be movable into open and closed positions. The top 21 includes a substantially

30 rectangular closed frame construction 22 having an upper wall 23 overlying said frame and a lower wall 24 arranged on the bottom side of said frame so as to define, with the frame 22, a dead air space 25. A diaphragm 26 fashioned 35 from a sheet of heat reflective material is arranged within dead air space 25 in a plane parallel to the plane of the walls 23 and 24. The diaphragm 26 has its marginal edges firmly secured to or within the frame 22 so as to divide 40 the dead air space 25 into two sections each of which is completely sealed from the other and from atmosphere.

The inside surface of the upper wall 23 of the top 21 and both surfaces of the lower wall 24 45 of said top are suitably coated with a heat reflecting substance 27 which may be applied thereto as by painting or spraying it thereon while in a liquid state. The entire interior surface of the radiator enclosure wall structure 50 similarly is coated with a layer of heat reflecting material 28 likewise applied as by painting or spraying.

It should be quite evident that when the radiator enclosure is positioned over the radiator indicated in dotted lines at 29 in Fig. 3, room air

may move freely into the enclosure through the screened front wall 16 and pass between and around the radiator 29 for discharge through the screened front wall 16. The heat radiating surfaces of the enclosure prevent the transmission of heat through the walls of the enclosure, consequently, the enclosure functions to a high degree of efficiency inasmuch as no heat is lost through said walls. The structure of the top 21, which includes five layers of heat insulating material and two dead air spaces, prevents the transmission of heat through to the upper wall 23 thereof, consequently, plants, flowers, or other objects which might be damaged by heat, may be safely placed upon the top of the radiator enclosure top. The construction of the radiator enclosure is such that it fits snugly to the floor and thereby eliminates convection of air into the base regions of the radiator and minimizes the circulation of dust and dirt particles which are a frequent source of annoyance.

It should be quite evident that the structure shown in the accompanying drawing may embody details of construction other than those illustrated so as to adapt the principles of the invention to enclosures of different shapes and sizes without departing from the spirit of the invention and the scope of the appended claim.

I claim:

In an upright radiator enclosure which includes front and rear walls and end walls, said front wall being provided with grille work, and all of the interior surface of the remaining walls

being heat reflective. A removable top overlying the upper ends of all the walls and closing off the enclosure to prevent escape of any air therefrom except via the grille work, said top being formed of a wooden rectangular closed frame having upper and lower wooden walls secured thereto to form a dead air space therein, a horizontally arranged diaphragm, secured to the frame on all sides thereof and dividing said space thereby into two independent dead air spaces, said diaphragm being formed of heat-reflective material, the bottom and top surfaces of the lower wall and the bottom surface of the upper wall all having coatings of heat reflecting substance whereby to prevent escape of heat from the interior of their enclosure.

TOM V. SAWYER.
